UNITED STATES PATENT OFFICE.

DORR E. FELT, OF CHICAGO, ILLINOIS.

TABULATING-MACHINE.

SPECIFICATION forming part of Letters Patent No. 694,955, dated March 11, 1902.

Application filed November 19, 1900. Serial No. 36,951. (No model.)

To all whom it may concern:

Be it known that I, DORR E. FELT, a citizen of the United States, residing in Chicago, in the county of Cook and State of Illinois, have 5 invented a new and useful Improvement in Tabulating-Machines, of which the following is a specification.

This invention is an improvement in computing tabulating-machines adapted to print 10 parallel columns of numbers side by side upon a more or less wide sheet of paper as distinguished from the narrow ribbon-paper heretofore commonly employed. Heretofore these machines have been provided with 15 alarms controlled by the paper and acting to give a signal when the printing reaches the bottom of the sheet, and I have shown such alarms in my Patents Nos. 628,176 and 644,287. Alarms, however, often fail of their object, as 20 the operators do not always heed them and do not always hear them, and it therefore frequently happens that the operator continues to go through the operation of setting up and printing numbers after the alarm is given and 25 after the bottom of the sheet has moved beyond the feed-rolls. In machines of this kind this causes serious trouble, as the numbers set up after the sheet has passed through the rolls are added by the numeral-wheels and printed 30 one on top of another at the same point upon the paper and must be subtracted before proceeding with the next column, or the entire column must be printed and added over again. To avoid this trouble is the main object of the 35 present invention, and I have succeeded in avoiding it, as well as in improving the machine in other respects, by providing the printing mechanism, and also the adding mechanism, with means whereby both may be absolutely locked as soon as the last line has been 40 recorded, and all further printing (except of totals) and adding be prevented prior to the shifting of the sheet for the next column. The action of these locking means is controlled by 45 the paper being printed. By thus locking the printing and adding mechanisms I avoid all danger of the adding of numbers which are not also properly recorded, and the operator is relieved of all care upon that sub- 50 ject, as the machine automatically locks when the printing approaches the bottom of the paper, and this branch of my invention con-

sists in the combination, with the printing and adding mechanisms of a tabulating-machine, of means for locking such mechanisms 55 automatically when a full column has been printed.

Another feature of the invention relates to the construction of the devices whereby the paper thus controls the locking devices. As 60 heretofore constructed the paper-roll has been provided with a single annular groove, into which a spring-pressed finger or wire is entered when not held from entering by the paper, and this finger in the act of entering 65 the groove sets in operation the alarm mechanism. In order to insure action by this finger when the bottom of the sheet moves beyond it, the spring actuating it must have a fair amount of strength, and in my use of 70 the device I found that sometimes the spring caused sufficient friction upon the paper to tear it, especially when the finger nears the bottom of the sheet, and the finger almost always caused an objectionable crease in the 75 paper. These evils I now remedy by employing a series of fingers spaced apart so as to act upon the paper at different points, thereby distributing the pressure of the spring upon the paper through a series of separated 80 planes, instead of a single plane, as heretofore. I thus obviate both the tearing and creasing of the paper, without in any degree detracting from the efficiency or certainty of action of the fingers. 85

The invention also embraces several other features of novelty which are fully explained in the description given below and pointed out in the claims.

In the accompanying drawings, forming a 90 part of this specification, Figure 1 is a plan view of a tabulator provided with my present improvements, partly broken away. Fig. 2 is a horizontal longitudinal section of the paper-carriage, partly broken away. Fig. 3 95 shows the rocking bar carrying the spring-fingers pressing upon the paper and controlling the locking mechanism. Fig. 4 is a perspective of the device for transmitting motion from the paper-controlled device to the locking mechanism. Fig. 5 shows the column-spacing bar of the paper-carriage. Figs. 6 100 and 7 are longitudinal vertical sections. Fig. 8 is a horizontal section. Fig. 9 is a detail sec-

tion. Figs. 10 and 11 are partial vertical sections. Fig. 12 is a partial horizontal section. Fig. 13 is a vertical longitudinal section of the complete tabulator, showing both the printing mechanism and the adding mechanism. Figs. 14 and 15 are detail views, the latter being in perspective.

In said drawings, 15 represents the keys; 16, the surrounding-frame; 17, the numeral-wheels; 18, the answer-printing plunger; 19, the operating-lever, whereby the ordinary printing, the adding, and the line-spacing are done; 20, the column-spacing and paper-reversing lever; 200, the type-segments; 21, the ink-ribbon spools; 22, the upper paper-roll and 23 the lower paper-roll, and 24 is the upper guide and 25 the lower guide, between which the paper X is inserted. The rolls and guides are supported in a laterally-movable paper-carriage composed of bars 47 and 470 and end connections 471.

The main cam, operated by lever 19 and causing many of the operations of the machine not necessary to be described here, is shown at 26. It operates the paper-feed rolls by means of a bent lever 27, pivoted to the cam and operating the crank-arm 28, fast on the shaft 29, which I call the "main" or "line" shaft. Shaft 29 also carries another crank-arm 30, to the outer end of which a pawl 31 is pivoted. This pawl engages a ratchet-wheel 32, fast on the sleeve 83, hereinafter mentioned, and encircling the angular shaft 33, which carries a pinion 34, meshing with the pinion 35, loose on the shaft 36 of the feed-roll 23 and operating said roll through the medium of a clutch consisting of the disk 37, sliding on the shaft and having a laterally-projecting pin 38 and a disk 39, attached to pinion 35, and having a series of openings 40, into which said pin is adapted to enter. The disk 37 forms one side of an annularly-grooved slide 41 and is constantly impelled toward pinion 35 by a spring 42, confined on the shaft 36 between the slide and the pinion 43, through which and the pinion 44 on the shaft 45 of the upper feed-roll said upper feed-roll is driven. The slide 41 is moved at will, so as to disengage the pin 38 from disk 39 by the elbow-lever 46, pivoted upon the spacing-bar 47, the end 48 of said lever entering the groove of the slide, as plainly shown at Figs. 2 and 8. Normally this clutch is closed, as in Fig. 2, but is shown disengaged at Fig. 8 in order to better disclose the construction. Pin 38 passes through a block 370, fastened to shaft 36 and interposed between the disks 37 and 39. By means of lever 46 the operator opens the clutch whenever desired and while pressing on the lever is free to turn the rolls in either direction without imparting movement to the shaft 33 or any of the parts actuated by it. Through the medium of the mechanism described the paper-rolls are actuated at each operation of the lever 19 and its cam and act to move the paper to the extent of a line-space at each actuation.

The locking of the printing and adding mechanisms when the bottom of the paper is reached in the tabulating operations is effected as follows: As shown clearly in Figs. 6 and 7, the edge 49 of cam 26 is serrated and adapted to be engaged by the serrated end of a lever 50, pivoted stationarily at 51 and having an upstanding arm 52, to which a spring 53 is attached, the power of this spring being exerted in forcing the lever into engagement with the cam. From the farther end of this lever a connecting wire 54 extends upward to a junction with the right-angle bent end 55 of a lever 56, which is pivoted centrally upon a shaft 560 stationarily supported at its ends. The other end 57 of this lever sets under and acts to lift a bar 58, which I call the "finger-bar" and which has a limited up-and-down swinging movement, being pivoted at its ends 59 in the carriage ends 471, the ends 59 being bent away from the plane of the bar, as seen at Fig. 3. This bar carries a series of fingers or feelers 60, projecting forward from it and registering with slots 61, formed in the paper-guides 25 and 24. These fingers are located close under guide 25 with their points extending through guide 25 and when the lever 56 is permitted to lift the bar 58 the fingers move from the position of Fig. 6 to that of Fig. 7. In the former they project into the path of the paper, but are prevented from entering guide 24 by the paper, and in the latter figure the paper having passed beyond them they rise and enter the slots in guide 24. The fingers are employed in such number as may be desirable to prevent such friction upon any part of the paper as might rupture, mutilate, or crease it.

It will be seen from what is above written that the cam will become locked as soon as the bottom edge of the paper has passed the fingers and the fingers are permitted to rise in obedience to spring 53. The paper thus controls the fingers and through them it also controls the locking of the cam, and while thus locked neither the printing mechanism or the adding mechanism, in so far as they receive motion from lever 19 or cam 26, can be operated, and consequently the operator is absolutely prevented from either printing or adding numbers after a full column has been recorded. The fingers 60 are depressed when inserting the paper by providing roll-releasing lever 46 with a pin 62, which when the lever is operated bears against the inclined end 63 of an arm 64, attached rigidly to the finger-bar 58 and rocks the bar, thereby carrying the fingers downward and admitting the paper freely. The annular grooves 65 in the roll 23 give room to the fingers 60 and enable me to position the fingers close to the rolls.

The machine contains the paper-reversing mechanism of my Patent No. 644,287, acting to reposition the sheet after the completion of one column preparatory to the starting of a fresh column, and which is best shown at

- Figs. 6 and 8. This mechanism consists of the pinion 71 on shaft 33, the train of gears 72, 73, 74, and 75, and the toothed segment 76, having internal teeth meshing with gear 75.
- 5 The segment is mounted loosely on shaft 77, and the hand-lever 20 is mounted on the same shaft and carries a stud 78, engaging a shoulder or projection 79 on hub of the segment. The regular line-feeding movements given
- 10 to the paper will, through the mechanism described, carry the segment step by step from the position of Fig. 6, in which its projecting lug 80 is close under the upper stop 81, to or toward its lowermost position, (shown at Fig.
- 15 7, in which the lug 80 is almost in contact with the lower stop 82,) the extent of the segment's movement depending on the number of lines printed, and when the column is completed the operator in order to return the
- 20 paper vertically has only to depress lever 20. He thereby, through the engagement of stud 78 with the shoulder 79, raises the segment to the upper position again, and in so doing imparts a backward rotation to the gears and
- 25 through them to the feed-rolls exactly equal in extent to the aggregate of the feeding movements received while the tabulating was being done, and consequently the top of the sheet will be returned to the plane in which
- 30 the printing was started. While I have shown stops 81 and 82 in position to engage the lug 80 on segment 76 at the end of the up and the downstrokes of the segment, I do not rely on those stops regularly to arrest the segment.
- 35 As already explained, the locking of the cam 26 by the lever 50 as the printing nears the bottom of the sheet acts to prevent any further feeding movement of the paper-rolls, so that no further downward impulses will be
- 40 given to the segment, and this occurs before the lug 80 strikes stop 82, and in the case of the up movement of the segment I provide another stop, located near the ratchet-shaft 33 and consisting of a pin 115, carried upon the
- 45 side of pinion 71, and a stop 116, consisting of a projection formed on the inner side of a vertical plate 117 and located where it may intercept pin 115 at or shortly prior to contact by lug 80 with stop 81. The pinion 71 is
- 50 thus arrested and with it the train of reversing mechanism. By thus arresting the reversing mechanism at the point where it first receives power I avoid the evils which would be caused by lost motion in the parts between
- 55 stop 81 and said pinion 71 and insure the stopping of the paper-rolls when they are reversed at the exact point at which they were positioned at the time of starting the printing. The engagement between pinion 71 and gear
- 60 72, which, with its companion gears 73, 74, and 75 is supported upon a stationary part of the machine, such as the side plate 160, is maintained during the lateral movements of the paper-carriage by mounting pinion 71
- 65 upon a sleeve 83, fitted to and turning with shaft 33 and held against moving with the shaft in the longitudinal movements of the

latter by a stationary bearing 84, encircling the sleeve between the ratchet-wheel 32 and an outstanding rim or flange 85, so that pinion 71 and gear 72 are never out of mesh. The bearing 84 is attached to plate 160, and the sleeve may be fitted to the shaft at one end only, as seen at 830.

For shifting the paper laterally in column-spacing I employ the following mechanism and operate it simultaneously with the reversing of the sheet, so that by means of the same motor device both movements may be accomplished. The reversing-lever 20 is connected by a bent link 95, pivoted to the lever at 96 to the short arm of an elbow-lever 97 by a universal joint, and lever 97 is pivoted stationarily at 98 and carries upon its long arm a pivoted pusher 99, adapted to engage the notches 100 in the spacing-bar 47. The pusher is normally held out of engagement with bar 47 by a rest 101, but is urged into engagement as soon as it moves off the rest by spring 102. The notches 100 are spaced 90 apart to agree with the width of the column-spaces, and at each actuation of the reversing-lever 20 the movement given thereby to the link and elbow-lever carries the pusher off the rest and moves it far enough beyond 95 the rest to shift the spacing-bar and with it the paper-carriage a column-space to the left. A stop 103 may be secured to the top of plate 160, where it will come in contact with the short arm of lever 97 and limit the movement 100 in one direction; but its use is optional. To prevent overthrow of the carriage in the shifting movements, an elbow-shaped latch 104 is employed and connected to elbow-lever 97 by a link 105. The link is freely joined to the 105 lever and is slotted at 106, where it joins the upper arm of the latch. The normal position of the latch is shown at Fig. 2, and by reason of the slot 106 it is not forced down into acting relation with bar 47 until the shifting 110 movement is almost complete. It enters notches 107, located between notches 100 and which have their abrupt side facing in the opposite direction from the abrupt sides of notches 100. To hold the carriage stationary 115 between the shifting operations and also to insure uniformity in its positioning, I employ a spring-pressed dolly-roll 108, entering notches 107. The roll is carried in the end of a pivoted bar 109, and the bar is pressed 120 downward at all times by a spring 110, joined at one end to the vertical part of latch 104 and at the other end to a bent lever 111, employing the pivot 112 of the bar as a fulcrum and bearing on a pin 113, inserted in the bar. 125 The notches 107 are cut from side to side of the bar, while notches 100 are cut only part way through, and consequently the dolly-roll 108 cannot enter the latter. The dolly-roll 130 does not effect an absolute lock of the carriage, but is easily forced to yield whenever it is desired to move the carriage by hand.

The machine may be used with ribbon or roll paper, as well as sheet-paper, by provid-

ing it with a support for the shaft of the paper-roll in proper relation to the paper-guides and paper-feed rolls, substantially as shown in my Patent No. 644,287, and by providing it also with the throw-off or disconnecting mechanism now to be described. At 86 is a hand-lever, which I term an "interlocking" lever. This lever is pivoted upon a stationary pivot 87 and carries at its lower end a **U**-shaped piece 88, which sets over pinion 71 without interfering in any way with the latter's rotation, (see Fig. 9,) and by means of this lever said pinion is shifted on the sleeve to a slight extent sufficient to draw the laterally-extending pin 89, carried by the pinion, from the opening in rim 85, with which the pin is adapted to be brought into register. When the pinion is locked to the sleeve by pin 89, it compels the reversing mechanism to move with it at each actuation of the paper-feed rolls, and thus carry segment 76 downward, so that the feed-rolls will be reversed and return the paper to its starting-point when the segment is returned by lever 20, as already described; but when the pinion is free from rim 85 the pinion does not turn with the sleeve in the line-spacing, and consequently the reversing mechanism remains idle, so that the ribbon-paper instead of the sheet-paper can then be used to receive the tabulations. By means of the lever 86 the reversing mechanism is readily thrown into or out of gear, as desired, in an instant of time, so that the machine is practically always ready for use with either sheet or roll paper.

It is very essential that when the reversing mechanism is reconnected to the feeding-shaft 33 the same teeth shall come in mesh that were in mesh at the time of disconnecting, because if different teeth are brought in mesh in reconnecting the stop-pin may not be in proper position relative to stop 116 at the end of the reversing operation, or the ratchet 32 might be stopped in some position in which its dolly-roll 130 would rest on top of a tooth instead of entering between adjacent teeth. To avoid any possibility of this kind, I provide means whereby the connecting and disconnecting can take place only when the parts are in a certain position. To this end, the vertical plate 117, already mentioned, is pivoted at its lower end on a stationary pivot 118 and is provided with an arm 119, positioned so it will be engaged by the pin 120 on the inner face of segment 76 just before the segment reaches its upper position. The plate also is provided with an opening 121, encircling the hub of the pinion 71, but larger than the hub, so as to permit a slight edgewise movement by the plate upon its pivot 118. The plate is positioned close to the pinion, so that said pin 115 will strike it and prevent the shifting of the pinion, except when the single small opening 122, located close under the stop 116, and the pin 115 are brought into register one with the other. This opening is adapted

to receive the pin, and thus to permit the pinion to be shifted toward plate 117 by lever 86 in effecting the disconnection of the reversing mechanism. A spring 123 constantly ⁷⁰ draws the plate in a direction which carries the opening 122 out of the orbit of pin 115, so that no opportunity is afforded to shift pinion 71, except when the segment overcomes said spring 123 and forces the plate over sufficiently to allow the pin to enter the opening. It will also be noted from Fig. 8 that pinion 71 has no intermediate position, but is either locked to the sleeve by pin 89 or is held against rotation by the entrance of pin 115 ⁸⁰ within opening 122 of plate 117 and that it can only be shifted from one of these positions to the other when the opening in the rim of the sleeve and the opening in the plate are both in register with their respective pins. ⁸⁵ It will also be observed that the slight movement allowed plate 117 is sufficient to carry the opening 122 into and out of the orbit of pin 115. The construction described permits the disconnecting and reconnecting of the reversing mechanism only when the segment ⁹⁰ 76, and consequently all the gears and the pin 115, are in one particular position and the dolly-roll 130 is seated between two of the teeth in ratchet 32, thus insuring that the identical teeth of all the intermeshing parts which were in mesh at the time the disconnecting took place are again brought into mesh and continue at all times, while connected to bear identically the same relation to one ¹⁰⁰ another. The plate 117 is steadied and guided at the top by the notched pin 124. From this paragraph the operation of stop 116 and pin 115 will be more fully understood. With the pin-stop over the pin and the pin 120 against ¹⁰⁵ the under side of the arm 119 no obstacle exists to the feeding of the paper, because the pinion 71 is free to move in the direction in which it moves when the paper is fed upward, and such movement carries segment 76 and ¹¹⁰ its pin 120 downward away from arm 119 and also carries pin 115 away from stop 116. The feeding of pin 120 downward allows spring 123 to act and move plate 117, so as to carry stop 116 out of the orbit of pin 115. The dolly-roll 130 is supported in a swinging arm 131, supported upon a stationary pin 132 and is normally urged toward the ratchet-wheel by ¹¹⁵ spring 133 through the medium of a bent lever 134, employing pin 132 as a fulcrum and exerting its power upon the pin 135, inserted in arm 131. The dolly-roll is forced away from the ratchet whenever the reversing-lever is actuated by means of the cam-lever ¹²⁰ 136, fast on shaft 77 and acting on the pin 137, secured in the dolly-carrying arm 131, the lever 136 having an inclined surface 138, adapted to move the dolly-arm in the direction which carries the dolly away from its actuating position. The spring 139, one end of which ¹²⁵ acts on the cam-lever and the other end of which is secured to a stationary stud 140, acts

to return the cam-lever and with it shaft 77 and the parts carried by it to their normal positions after each reversing operation.

The machine is adapted to be used with sheet-paper of a predetermined length—say, eighteen inches—but any shorter length may be used. If paper longer than the maximum length for which the machine is intended be inserted, the fingers 60 would be prevented from acting before the lug 80 reaches the stop 82, because the longer paper at that time would still be interposed between the fingers and the upper guide 24, and consequently in such cases no locking action by lever 50 would be caused and the operator would be at liberty to continue setting up and printing numbers, although no feed of the paper takes place after lug 80 is in actual contact with stop 82. The result just described might also be caused by faulty positioning of a sheet of the prescribed length—that is to say, so that its bottom edge instead of passing entirely beyond the fingers at the time of the printing of the last number remains over them, so as to prevent their operating. I therefore provide other means than those already described for causing the locking of the cam when the fingers are prevented from operating, as above set forth. To this end lever 50 is provided with a projecting lug 141, as seen at Figs. 6 and 7, and the segment is provided with a contact-piece 142, so positioned that when the segment approaches its lowermost position the contact-piece will engage said lug and force lever 50 against the cam and thus lock the cam in the same manner as when it is caused to be locked by means of the fingers 60. The contact-piece 142 is made yielding, being pivoted at 143 at one end and pressed outward at its other end by the spring 144. A pin 145 limits the action of the spring. The connecting-rod 54 is joined to the lever 50 by a yielding joint constructed as seen at Figs. 6 and 7. The end of the rod is bent at right angles and is inserted in a vertical slot 146 in the lever, and a spring 147 secured to the lever bears at one of its ends upon the bent end of the rod. This flexibility in the connection avoids any danger of the finger mutilating the paper.

At Figs. 11 and 12 I show my improved mechanism for operating shaft 560, by which the hammers are released and caused to print and which I therefore call the "printing-shaft." Upon the side of the machine opposite to that upon which the operating and reversing levers are located this shaft is provided with a segment-shaped crank 150, the normal position of which is illustrated at Fig. 11 and in which it rests against a stop 151, secured in the side plate 161. To this crank are attached two slotted links 152 and 153, the former connecting the crank 150 with the crank 154 on the main shaft 29, receiving motion from the operating-lever, and the latter connecting the crank 150 to the end of the lever 155, by which the printing of the to-

tais is caused. Link 152 is slotted to permit crank 154 to move through the major portion of its stroke before actuating the printing-shaft, and the link 153 is slotted to permit lever 155 to move partially through its stroke before operating the same shaft. The total-printing lever is also joined by a slotted link 157 to a crank 156, fast on the extension 290 of shaft 29 and which is permitted to turn independently of shaft 29, being like shaft I³ of Patent No. 644,287 in that regard and also in its purpose and function. A stop 158 on crank 154 limits the movement of crank 156 downward. With the construction set forth the actuating of shaft 29 by the operating-lever gives no motion to the total-printing lever, although all the other parts mentioned in this paragraph are moved, and, on the other hand, the actuating of the total-printing lever gives little or no motion to shaft 29.

For changing the machine from single-line-space to double-line-space printing and back from the latter to the former I employ the following devices: At 90 is a lever stationarily pivoted at 91 and having its lower end enlarged on one side, as seen at 92, Fig. 8. As shown, the lever is not acting, and consequently the pawl 31 will move the ratchet to the extent of two teeth at each actuation and the printing will be double-spaced; but if the lever 90 be shifted, so as to carry its side enlargement close up to the ratchet, the pawl, which is wider than the ratchet, will ride over the enlargement before it engages the ratchet, and consequently cannot engage the latter until its down movement is half made, and consequently it imparts only a one-tooth movement to the ratchet and the printing will be single-spaced.

The locking-lever 50 is released from cam 26 whenever the total-printing lever 155 is operated by an arm 170, extending downwardly from the shaft 171, to which lever 155 is fast, and the pin 172 on lever 50, which encounters arm 170. This will be understood best from Fig. 11. The same figure also shows a bar 173, actuated by a stud 174 on shaft 171 and serving to tip very slightly the hammer-housing, of which a portion is shown at 175.

The keys are each provided with an offset or bend 176 on their stems, adapted to engage the segment-levers 177, the offsets being graduated in position, so that each key will be able to impart to the lever the proper amount of movement. Each of the levers is provided with teeth which mesh with the pinions 178 upon the same shaft with the numeral-wheels, and each of said pinions actuates one of the numeral-wheels. The carrying-lever is shown at 179. The keys are adapted to be set in advance of the adding and printing, and to this end they are provided with shoulders 180, adapted to be engaged by spring-catches 181, carried on frame 182, sustained on cranks 183, one of said cranks being on the shaft 184, provided with a second crank 185, the upper end of which carries a

pin 186, working in a slot 187 in the main cam 26. The catches are released from the keys by a horizontally-moving frame 188, mounted on the frame 182. The downward movement 5 of frames 182 and 188 takes place when the hand-lever 19 is operated and carries any key which may have been previously set down with them, and such key imparts a movement to its corresponding segment-lever proportioned to the power of the key, and the segment-lever in turn actuates its corresponding numeral-wheel to a proportionate extent and also positions one of the type-segments 10 200 in printing position, the type-segments 15 being pivoted at 201 and connected to the segment-levers by links 202. It will be understood that there are a series of nine keys for each denomination embraced in the machine and that such keys are duplicates of 20 the one shown; also, that there is a separate numeral-wheel and segment-lever for each denomination together with carrying devices for all the wheels except the lowest. The releasing movement of frame 188 is caused by 25 means not shown, but which may be seen in my Patent No. 568,021 of September 22, 1896. The paper seen at X is impressed upon the type by pivoted spring-actuated hammers 203, of which there is one for each denomination 30 and which are normally held out of action by detents 204, but are released from the detents by the tailpiece 41, actuated in part by the segment-levers and in part by a swinging cross-bar 206 and the hammer-releasing 35 frames 207. The action of this hammer mechanism is fully set forth in my Patent No. 644,287 of February 27, 1900. The paper enters the machine between the guides 24 and 25, is fed by rolls 22 and 23, and guided upward by guides 208.

I claim—

1. The combination of an adding mechanism, printing devices, a paper holder and feeder one being laterally shiftable relative 45 to the other means for operating said mechanism and devices at will, and automatic mechanism acting when the bottom of a sheet is reached for preventing the actuation of said adding mechanism.
2. The combination of an adding mechanism, printing devices, means for operating said mechanism and devices at will, a paper holder and feeder adapted for the holding of sheets of paper, and automatic mechanism released 50 by the bottom edge of the sheet for preventing the actuation of said adding mechanism.
3. The combination of an adding mechanism, printing devices, means comprising finger-keys for operating said mechanism and 60 devices at will, a laterally-shiftable paper holder and feeder, and automatic mechanism acting when the bottom of a sheet is reached for preventing the actuation of said adding mechanism.
4. The combination of an adding mechanism, printing devices, means comprising finger-keys for operating said mechanism and 65

devices at will, a laterally-shiftable paper holder and feeder, and means controlled by the paper for preventing the actuation of said adding mechanism at a predetermined time. 70

5. The combination with the operating-lever and its cam, of a lever 50 controlled by the paper and locking the cam when a full column has been tabulated, substantially as 75 specified.

6. The combination with the operating-lever and its cam, of a spring-actuated lever 50 engaging the cam and means whereby the paper controls said lever 50, substantially as 80 specified.

7. The combination with the printing mechanism of a tabulator, of a laterally-movable paper-carriage, means for locking said mechanism, and devices controlling said locking 85 means, consisting of a series of spring-pressed fingers supported in said carriage and bearing upon the paper at separated points and mechanically connected to the locking means, substantially as specified. 90

8. The combination with the printing mechanism of a tabulator, of means for locking said mechanism and devices for controlling said locking means, consisting of a series of spring-pressed fingers bearing upon the paper 95 at separated points and yielding connections between said locking means and said fingers, substantially as specified.

9. The combination in a tabulator with the printing mechanism, of means for locking said mechanism when a full column has been tabulated, and mechanism for reversing the sheet acting to cause said locking means to act, substantially as specified. 100

10. The combination in a tabulator with the printing mechanism, of means for locking said mechanism when a full column has been tabulated, means whereby the paper may cause 105 said locking means to act upon the completion of a column, and mechanism for causing said locking means to act in cases where the paper is too long or is wrongly positioned, substantially as specified. 110

11. The combination in a tabulator with the printing mechanism, of means for locking said mechanism when a full column has been tabulated, means whereby the paper may cause 115 said locking means to act upon the completion of a column, and paper-reversing mechanism acting also to cause said locking means to act 120 in cases where the paper is too long, substantially as specified.

12. In a tabulator, the combination with means for feeding the paper and printing mechanism for printing the numbers or 125 amounts tabulated both operable at will, of a series of widely-separated spring-pressed fingers bearing against different portions of the paper in proximity to the feeding means, and means for locking said mechanism controlled 130 by said fingers, substantially as specified.

13. The combination with the reversing mechanism of means for arresting the reversing movement located at the point where it

receives power in the line-feeding movements, substantially as specified.

14. The combination with the reversing mechanism of means for arresting the reversing movement consisting of the pin 115 on the initial member of the mechanism, and a stop 116, substantially as specified.

15. The combination with a paper-reversing mechanism embracing an initial pinion receiving impulses from the paper-feed mechanism in the line-spacing movements, of a stop-pin 115 carried by said pinion, and a relatively stationary projection or stop 116 adapted to engage said pin, as the reversing mechanism completes the reversing operation, substantially as specified.

16. The combination with the paper-carriage of means for feeding the carriage in column-spacing, a device for arresting the carriage and link 105 slotted at 106 and actuated by the feeding means, substantially as specified.

17. The combination with the paper-carriage of means for feeding the carriage in column-spacing, means for preventing overthrow of the carriage, and a dolly-roll acting to center the carriage in its several positions, substantially as specified.

18. The combination of a paper-carriage having a spacing-bar with oppositely-faced notches, a feeding-pusher, an overthrow-preventing latch and a dolly-roll, substantially as specified.

19. The combination of a paper-carriage having a spacing-bar with oppositely-faced notches, a feeding-pusher, an overthrow-preventing latch and a dolly-roll, the latch and roll being both connected to the pusher, substantially as specified.

20. The tabulating-machine adapted to be used with either sheet or roll paper, and having a mechanism for reversing the sheet-paper, the combination of the paper-feed mechanism, said reversing mechanism and a device connecting said reversing mechanism with the paper-feed mechanism and changeable as to position to disconnect and reconnect the mechanisms, and means for regulating the disconnection and reconnection so that both always take place when the members of the mechanisms are in the same relative positions, substantially as specified.

21. The combination in a tabulator, of mechanism for feeding the paper in line-spacing, mechanism for reversing the paper geared to said feed mechanism by a separable connection, and means for regulating said connection so that it can only change position while the mechanisms are in one position, substantially as specified.

22. The combination in a tabulator, of mechanism for feeding the paper in line-spacing, mechanism for reversing the paper geared to said feed mechanism by a shifting pinion, having a lateral pin 115, and a plate 117 surrounding the pinion-shaft in proximity to the pinion and having a single opening 122 which

said pin must enter to permit the shifting of the pinion, whereby the pinion is prevented from being shifted to disconnect the mechanisms except at one point, substantially as specified.

23. The combination in a tabulator, of mechanism for feeding the paper in line-spacing, mechanism for reversing the paper geared to said feed mechanism by a shifting pinion having a lateral pin 115, a pivoted plate 117 surrounding the pinion-shaft in proximity to the pinion and having a single opening 122 to receive said pin and acting to prevent the shifting except when the pin and opening are in register, and means whereby the registering mechanism moves said plate to bring the opening into the orbit of the pin, substantially as specified.

24. The combination with the paper-feed mechanism, paper-reversing mechanism, and separable means for connecting and disconnecting said mechanisms, of means for preventing connecting or disconnecting except when the members of the mechanisms are in certain relative positions, substantially as specified.

25. The combination with the operating-lever and its cam, and the locking-lever 50, of the total-printing lever and means whereby the latter releases said locking-lever, substantially as specified.

26. The combination with the operating-lever and cam, of devices for causing the locking of the lever and cam consisting of a lever engaging the cam, a series of separated spring-pressed fingers 60 mounted upon a swinging bar and extending close up to the feed-rolls, a slotted guide above the paper into which said fingers move when the paper has passed, and connections between said bar and the lever engaging the cam, substantially as specified.

27. The combination with the printing mechanism, a laterally-movable paper-carriage and the devices whereby the printing mechanism is locked upon the completion of a column, of a series of separated fingers bearing upon the paper as it enters the feed-rolls, a bar pivoted at its ends in said carriage so it may swing and upon which said fingers are secured, connections between said bar and the locking devices, and a spring pressing said fingers against the paper, substantially as specified.

28. The tabulating-machine having a laterally-movable paper-carriage adapted to receive wide sheets, printing mechanism, means for feeding the paper vertically at each impression, and means whereby the actuating devices of said printing mechanism and said paper-feeding means may be automatically locked upon the completion of a full column, whereby the further operation of the printing mechanism is arrested and the operator is notified that the sheet must be shifted or replaced, substantially as specified.

29. The combination with the feed-rolls and

actuating mechanism of a series of spring-pressed fingers projecting into the path of the paper, in proximity to the feed-rolls, a lever for moving and retaining the fingers out of said path while inserting the paper, said lever being located where it may be operated by the same hand which turns the rolls, and means connected with said fingers for controlling the actuating mechanism, substantially as specified.

30. The combination with the adding mechanism of a tabulating-machine and the device by which such mechanism is operated, of means for locking said operating device when a complete column has been tabulated, substantially as specified.

31. The tabulating-machine having a laterally-movable paper-carriage, and printing mechanism having finger-keys and adapted to print columns not exceeding a predetermined length, and also having means for locking the printing mechanism upon the completion of a full column irrespective of the lateral position of the carriage, whereby the further operation of the machine is arrested and the operator is notified that the sheet must either be shifted or replaced, substantially as specified.
